UNITED STATES PATENT OFFICE.

GUIDO HORN, OF WEISSENSEE, BERLIN, GERMANY.

BRAIDING MACHINE.

1,409,297.

Specification of Letters Patent. Patented Mar. 14, 1922.

Application filed December 19, 1913. Serial No. 807,719.

(GRANTED UNDER THE PROVISIONS OF THE ACT OF MARCH 3, 1921, 41 STAT. L., 1313.)

To all whom it may concern:

Be it known that I, GUIDO HORN, a subject of the German Emperor, residing at Weissensee, Berlin, Germany, have invented 5 new and useful Improvements in Braiding Machines, of which the following is a specification.

Machines for producing braided coverings on round bodies are known in which the carriers, that carry the one series of bobbins along a circular path, are propelled by actuating members fixed to a rotating body. These devices generally consist of several parts and leave only very little room for the 10 passage of the threads of the other series of bobbins that travel in the opposite direction to the first series. By my present invention I provide actuating members which at all times positively engage with the carriers, so 15 that these latter are continuously positively propelled, whilst allowing ample room for the passage of the oppositely moving threads.

The guiding of the outer threads, whose 20 bobbins are attached to a rotating table or turret, has hitherto been accomplished by moving parts of most different kinds and also by thread guiding levers or switches. In the present invention thread switches are 25 also used, but the cams for moving these switches travel in a cam groove made in a spherical surface all points of which are at an equal distance from the central braiding point. By arranging the cam groove in a 30 spherical surface of this kind it is ensured that the groove at all points fully faces the central braiding point and will at all points present its entire lateral walls to the switch cam thus preventing axial displacements of 35 the cams and uneven wear. This arrangement of the cam groove also ensures that the ends of the thread switches that pay out the threads are always kept at a uniform distance from the braiding point, so that all 40 changing of the lengths of the travelling threads is obviated. This will be more fully understood from the description of the drawings.

By this design a machine is produced that 45 operates fast and with small driving power, and that has the smallest number of parts imaginable in a machine in which the outer threads are positively guided.

Machines according to the present inven-

tion may be made for various styles of braid. 55 The production of a variety of braids is not usually provided for in one and the same machine, but is possible by changing a cam groove ring.

The machine illustrated herein produces 60 the most generally employed whip lash braid.

Fig. 1 shows half of the machine in elevation and half in section.

Fig. 2 is a plan view,

Fig. 3 a view showing successive positions of an actuating member and an inner bobbin carrier on an enlarged scale.

Fig. 4 is a view showing the product made by my machine.

Fig. 5 an elevation of a modification of the machine and

Fig. 6 illustrates the improved form of cam groove in contradistinction to the cam grooves hitherto employed for shifting the 75 thread guide levers or switches.

On the ground plate 1 the middle axis 2 is fixed about which the long hub 3 of the inner carrier propeller 4 is rotated by the bevel driving gear 8 that meshes with the 80 bevel gear 5 that is splined to the hub 3. The gears 5 and 7 are rotated in opposite directions by the gear 8. The rotor or turret 6 has a circular runway or race 9 upon which the bobbin carriers 10 slide. Holding 85 brackets 11 for supporting the bobbins 12 are attached to the carriers 10. The inner faces of the carriers 10 have curved slots 13, Fig. 3, adapted for engagement with the upwardly bent curved ends of the actuating 90 or propelling members 14. These actuating members are provided with pivots 15 that are revolubly mounted in the carrier propeller 4. A pin or follower 16, which travels in a cam groove 17, is also attached to each 95 actuating member. The actuating members 14 are so arranged that, during their travel along their circular orbits, their arc-shaped ends rock up and down and alternately engage with the slots 13 at both ends of the 100 carriers. An arc-shaped end of an actuating member that is moving downwards will remain in engagement with its slot and continue propelling the carrier until the other end has meshed with its corresponding slot 105 and assumed the propelling function. The propulsion by the actuating member is thus continuously positive and uniform.

The cam groove 17 is made in the inner surface of the rotor 6 the upper edge of which forms the runway 9. Each point of the cam groove that engages with the cam 5 of an actuating member is on a radial line drawn from the pivot of the particular actuating member. The ring portion of the middle rotor that takes the cam groove may be made in the shape of a cylinder as shown.

10 Indentations 18 for the passage of the outer threads beneath the carriers are provided in the runway 9. Suspended from the under side of the rim of the rotor 6 are the bobbin brackets 19 with the outer 15 bobbins 20. On the periphery of the rotor 6 are mounted the posts 21 which support the thread guiding levers or switches 22. The thread switches rock on pivots 23 and are provided with pins 24. Each pivot 23 20 has a small hook arranged on its inner end which guides the thread that passes from the bobbin 20 through a hole in the post 21.

Erected on the ground plate 1 are pillars 25 that support the fixed peripheral cam-groove ring 26. A cam groove 27 is cut into this ring 26. The inner surface of the ring 26 constitutes a section of a sphere, the object of this arrangement being to cause the cam groove to be directed at all points 30 radially towards the center of the imagined sphere, this center being, in the described machine, the point of braiding M Figs. 1 and 2. The central lines of the axes or pivots 23 and pins 24 also intersect at the 35 point M. The result of the radial directions of the switch pivots 23 and cams 24, combined with the radial direction of the cam groove at all its points, is that every cam 40 24 not only sinks into the cam-groove to an equal depth throughout the whole of its travel in the groove, but is also always directed straight towards the point M, so that it never rocks over towards the one side of the groove or the other and jams. 45 These results of the spherical surface for the cam-groove are illustrated in comparison with a cam groove on a flat surface in Fig. 6 parts A, B, C and D. Fig. 6 part A shows a cam-groove viewed from the point 50 of braiding. The thread switch is shown by solid lines in a horizontal position and by broken lines in an upwardly slanting position and a downwardly slanting position. Part B shows a top view and a cross section of a cam-groove arranged according to the invention on a spherical surface. Parts 55 C and D illustrate cam-grooves on flat surfaces and from the cross sections of these parts of Fig. 6. It will be apparent that 60 the cams assume slanting positions in their cam grooves instead of always fitting squarely in the groove as shown in part B of Fig. 6.

The outer thread is led from the bobbin 65 20 through the post 21 over the pivot 23 and

thence over the end of the thread switch to the point of braiding. As the switch always keeps at an even distance from the point of braiding in all positions, the length of the thread will also remain constant.

70 The machine operates as follows:

It will be assumed that the rotor 6 with the outer bobbins 20 revolves from left to right. The carrier propeller 4 will then turn towards the left and the actuating members 75 14 will propel the carriers 10 with the bobbins 12 in the opposite direction to the outer bobbins. Since the cams 24 Figs. 1 and 2 travel in the fixed cam-groove 27 the thread switches 22 will rock up and down 80 and impart sinuating motion to the outer threads causing them to alternately pass over two inner bobbins and then under two other inner bobbins. The switching of the thread from a lower position to a higher position 85 and vice versa takes place in the intermediate space between two inner bobbins. The threads move down into their lower positions in the indentations 18 of the runway 9. When a thread has reached the lower end of 90 an indentation 18 the next bobbin carrier passes over it. During the passing of the carriers over the outer threads each actuating member 14 is shifted by the co-operation of its pin or follower 16 with the cam-groove 17 95 on the inner surface of the rotor so that each end of the member 14 moves down beneath the lowest point of each indentation or thread which it passes. In Fig. 3 three consecutive positions I to III are shown that 100 an actuating member 14 assumes when passing an outer thread. In the first position I a carrier travelling in the direction of the arrow and propelled by the rear end of the actuating member 14 has passed over a 105 thread in the indentation 18 up to its forward slot 13 which is at that time out of engagement with the front curved end of 14. In Position II the middle of the carrier II has reached the indentation 18 and both ends 110 of the actuating member 14 are in engagement with their slots. In position III the rear end of 14 is out of engagement with the rear slot and room is thus left for the outer thread in 18 to pass between the curved end 115 of the actuating member 14 and the bobbin carrier 10.

The manner in which the style of braid shown in Fig. 4 is produced by the machine may be explained with the aid of Fig. 3. a, 120 b, c, d and e are outer threads, and f, g, h, i and k are inner threads in the illustrated 24-bobbin machine. Thread a has passed beneath the threads h and g, after having previously passed over the threads k and i. 125 The thread b lies above the threads i and h and, as will be seen from the lower position of the cam of its switch, will now pass beneath the threads g and f. Thread c lies beneath the threads k and i and will now pass 130

over the threads *h* and *g* and so forth. It would also be found that each inner thread passes alternately over and under sets of two threads. Fig. 4 illustrates the kind of braid 5 produced.

In the design described in the foregoing description a runway is provided for the carriers of the inner bobbins that is fast with the rotor that carries the outer bobbins and 10 consequently rotates at the same speed. Fig. 5 represents a modification in which the runway and the cam-groove for the actuating members of the inner bobbins are stationary. This construction requires the division of 15 the runway into sections 9^a and 9^b, these sections being supported alternately by the middle stationary hollow axis 2 of the machine with the middle support 6^a and by the outer suspended ring 6^b. The middle support 20 6^a is made ring-shaped beneath the runway so as to adapt it to the cam-groove 17. The outer threads are so guided that they pass over the runway sections 9^a and beneath the suspended runway sections 9^b. Spaces 25 18^a are provided between the runway sections 9^a and 9^b so that the outer threads may sinuate above, between and under the corresponding runway sections.

All the other parts have the same signs of 30 reference as the corresponding parts in the Fig. 1 already described. It need only be mentioned that the hub 3 of the carrier propeller 4 revolves in the hollow axis 2 of the machine and that the inner bobbins 12 are 35 mounted on the inner sides of the carriers 10. The operation of both machines is similar, so that the operation of the modification need not be described.

It may be mentioned that the cam-groove 40 which oscillates the actuating member 14 that propels the inner bobbins is shown in Fig. 5 in two different shapes. In the right half of the machine, which is shown in sec-

tion, the form of the cam-groove is such that the actuating member is not shifted when 45 the outer thread travels above the carrier in crossing the actuating member, as a shifting of the actuating member to allow the outer thread to pass in then obviously unnecessary. On the left side of the machine in Fig. 5 a 50 cam groove of uniform shape which is easier to execute is shown. This would cause unnecessary shifting of the actuating members at the points where the outer threads pass over the inner bobbin carriers. 55

I claim:

1. In a braiding machine, the combination with two sets of thread supplies revolving in opposite directions, the threads from the one set sinuating through the threads of the 60 other set, of switches to control the sinuating thread supplies, and a member having a cam-groove on a concave spherical surface thereof for shifting the said switches, all points of the spherical surface being at an 65 equal distance from the braiding point of the machine.

2. In a braiding machine, the combination with two sets of thread supplies revolving in opposite directions, the threads from the one 70 set sinuating through the threads of the other set, of switches to control the sinuating thread supplies, and a separate cam ring extending around the outside of the rotor and having a cam groove therein, and pins in the 75 said groove for shifting said switches, said cam groove being so shaped as to always keep the middle line of the cam directed straight toward the braiding point of the machine. 80

In testimony whereof I hereunto affix my signature in the presence of two witnesses.

GUIDO HORN.
